COIN-CONTROL MECHANISM

Edwin Parre, Aurora, Ill., assignor to Stoner Manufacturing Corporation, Aurora, Ill., a corporation of Illinois

Application March 9, 1953, Serial No. 341,057

8 Claims. (Cl. 194—55)

The invention relates to coin-controlled vending machines and more particularly to improvements in that type of machine which is manually operated by the customer following the deposit of a coin or coins.

Vending machines of this character include mechanism responsive to the deposit of a coin or coins effective to selectively release locking mechanism normally preventing the operation of the vending mechanism. One form of such mechanism includes a plurality of lock gates normally lying in the path of slidably reciprocable means, which gates are selectively moved into and held in an unlocking position by the presence of a coin in close association therewith. Heretofore, each lock gate had a cam arm associated therewith for direct engagement by the coin. In such devices the cam arm slides along the lock gate during machine operation to unlock the lock gate. Prolonged use under service conditions results in wearing of the cams and the engaged surfaces of the lock gate to such a degree that the lock gates fail to move the distance necessary to release the locking mechanism. When this occurs the machine is no longer serviceable.

The present invention is concerned with the provision of a coin-controlled locking mechanism embodying novel structural characteristics adapting the mechanism to long service with a minimum amount of wear and it is one of the objects of the invention to provide such a mechanism.

Another object of the invention is to provide a coin-controlled locking mechanism for a vending apparatus wherein there is no sliding between the locking gate or parts associated therewith and the coin during machine operation.

Another object is to provide a lock mechanism, including unlocking means which is free from all contact by the coin-moving means unless a coin is actually in place for the specific purpose of unlocking the lock mechanism.

Another object is to provide a locking gate for a coin-controlled mechanism with novel coin engaging means.

Another object is to provide a coin-control structure embodying the features of the invention and which is not costly to manufacture and assemble, is tamper-proof and is positive in operation.

With the foregoing and other objects in view which will appear as the description proceeds, the invention consists of certain novel features of construction, arrangement and combination of parts hereinafter fully described, illustrated in the accompanying drawings, and particularly pointed out in the appended claims, it being understood that various changes in the form, proportion, size and minor details of the structure may be made without departing from the spirit or sacrificing any of the advantages of the invention.

For the purpose of facilitating an understanding of my invention, I have illustrated in the accompanying drawings a preferred embodiment thereof, from an inspection of which, when considered in connection with the following description, my invention, its mode of construction,

2

assembly and operation, and many of its advantages should be readily understood and appreciated.

Referring to the drawings in which the same characters of reference are employed to indicate corresponding or similar parts throughout the several figures of the drawings:

Fig. 1 is an elevational view of the coin control mechanism embodying the features of the present invention and illustrating it mounted upon the right-hand side of a vending machine and showing portions of one of its walls broken away.

Fig. 2 is an elevational view of the coin control mechanism viewed from the opposite side to that in which it is shown in Fig. 1.

Fig. 3 is a horizontal sectional detail view taken substantially in line 3—3 of Fig. 1 and showing, in association therewith, a portion of the vending control mechanism.

Fig. 4 is a fragmentary sectional view similar to Fig. 3, but showing the lock gate in the position assumed upon initial actuation of the coin control mechanism.

Fig. 5 is a sectional detail view similar to Fig. 4, showing the parts in the positions assumed at the completion of a cycle of operation.

Fig. 6 is a perspective view of the lock gate and its cam element.

The invention is concerned with a coin control mechanism and more particularly with the locking gate construction which is constructed to remain serviceable over a long period of time because wear is minimized.

30 A vending machine of the general character to which the novel coin control mechanism is best suited is fully disclosed in Stoner et al., Patent No. 2,324,040, granted July 13, 1943, and because the vending mechanism per se, including the coin selector, the plunger-actuated vending mechanism and the stacks for the merchandise constitute no part of the present invention, they are not disclosed in detail in the drawings accompanying this application. The mechanism embodying the present invention is mounted on the right-hand side of the vending machine when the machine is viewed from the front.

35 The coin selector is, of course, of a type that will reject all false coins, bent coins or coins of a wrong denomination and accept 5¢ pieces only. The vending machine with which this mechanism is associated is, therefore, adjusted to deliver to the customer merchandise valued at five cents, ten cents and twenty cents. It will become obvious, however, that the feature of the present invention can be embodied in coin control devices which operate with coins of other denominations and in other numbers.

Referring now to the accompanying drawings the reference character 11 (Fig. 1) designates generally a stack, of which there may be several, arranged side by side in a vending machine, and within which is disposed the commodities to be vended. The novel coin control mechanism, generally indicated at 12, is mounted upon the right-hand side of the stacks 11 and its construction and operation will be described in detail presently. The coin control mechanism has associated with it a coin selector, indicated generally at 13 (Fig. 2) which may be of any conventional construction and includes a raceway 14 through which coins accepted are delivered to the coin control mechanism.

65 The coin control mechanism 12 includes a main plate 15 to which is attached an auxiliary plate 16 by means of screws or rivets 17. Means is provided preferably by upsetting the area of either or both plates at the openings for the rivets or screws 17 to maintain the plates 15 and 16 in spaced relationship with the distance between them being slightly greater than the coin for which the mechanism is designed. In the embodiment shown the space between the plates 15 and 16 is of a size slightly greater

than the thickness of a 5¢ piece. The main plate 15 is substantially rectangular in shape and may be provided at its bottom with a base flange 18 to afford means for securing the coin control mechanism on the vending machine. The upper edge of the auxiliary plate 16 is offset, as at 19, to constitute mounting means for the coin selector 13.

The auxiliary plate 16 is provided with a plurality of relatively narrow slots 21 for the accommodation of sliding members 22. Three such sliding members are provided and, upon referring to Fig. 1 which best illustrates their construction, it will be observed that the members 22 are arranged edge to edge and that the two lowermost sliding members have recessed ends 23. The uppermost sliding member 22 has a pair of recesses 24 provided in its inwardly disposed end. These four recesses adapt the coin control mechanism to accommodate four coins during one operation of the machine. Each member 22 also has a portion extending perpendicular therefrom, as at 25 (Fig. 2), which portions extend through the respective slots 21.

Upon referring to Fig. 3 it will be observed that the projecting portion 25 of the upper member 22, is notched at 26 to receive the end 27 of an operating lever 28. There are three such levers associated with the coin control mechanism but inasmuch as these levers constitute a part of the conventional vending mechanism only one is shown; it being understood, of course, that the remaining two levers which are not illustrated cooperate one with each of the two lower slide plates 22. During machine operation, at which time a piece of merchandise is to be vended, one or more of the levers 28 is actuated in such manner as to move its free end 27 to the right, as viewed in Fig. 3. When this occurs the sliding member associated with the lever being moved is shifted to the right. Such sliding movement of the sliding members 22 is, however, limited by the presence of lock gates 29, one or more of which is associated with each sliding member. These lock gates are alike and are constructed in the manner best illustrated in Fig. 6. As there shown, the lock gate 29 includes parallel side walls 31 and a connecting end wall 32. The side walls have aligned openings 33 through which is extended a pivot pin 34 (Fig. 2). The pivot pin 34 is common to all of the lock gates and it is securely mounted on the auxiliary plate 16 by having its ends journaled in ears 35 and 36 which preferably are struck out of the auxiliary plate 16.

When the lock gates are mounted in the manner shown in Figs. 2 and 3, a lug 37 provided on an edge of the end wall 32 of each lock gate, extends through a respective opening 38 in the auxiliary plate 16 so as to dispose the lug in the space between the main plate 15 and auxiliary plate 16. Springs 30 retain the lock gates in the locking position shown in Fig. 3. It should be quite obvious that with the lugs 37 projecting into the space between the two plates, sliding movement of the sliding member 22 is limited. It is, therefore, necessary to provide means for selectively rotating one, two or all of the lock gates about the pivot pin 34 a distance sufficient to lift the lug or lugs out of the path of the respective sliding members before said members can be shifted to the right (Fig. 3) so as to complete a cycle of operation.

The lifting or rocking of any one of the lock gates 29 is determined by the presence or absence of a coin or coins in the path of the sliding member to be shifted. In Fig. 1 there are illustrated four coins. As a consequence, upon machine operation, all three sliding members 22 may be shifted through a complete cycle of sliding operation. The specific mode of operation whereby any one of lock gates 29 is rocked so as to remove its lug 37 from the space between the plates is perhaps best illustrated in Figs. 3, 4 and 5.

Upon referring to Figs. 1 and 3 it will be noted that four coins 39 are located between the main plate 15 and the auxiliary plate 16 to the right of the lugs 37 on the

lock gates 29. When the machine is actuated to shift, for example, all four sliding members 22, illustrated in Fig. 1, said sliding members will move to the right until the end of their recesses 23 and 24 abut the related lugs 37 (Fig. 3).

During this movement of the sliding member the prongs 40 defined by the recesses 23 and 24 are carried into contact with the coins 39 and cause said coins to be pushed to the right in advance of the sliding members 22. When this occurs each coin 39 becomes actively engaged with a cam element 41, one carried by each of the lock gates 29. Specifically, the cam element 41 is pivotally mounted at 42 and it includes a cam surface 43 which terminates at one end in a finger 44 and at its other end in a deep recess 45, defining a second finger 46. Referring again to Fig. 3 the cam 41 is held normally in the position there illustrated by means of a torsion spring 47 so as to locate the recess 45 thereof in such position as to admit the coin 39. The manner and sequence of movement of the sliding members 22 will be described presently, 20 it being sufficient at this time to describe the action of but one of said members.

Upon initial sliding of a sliding member 22, which carries the coin or coins 39 in advance of it, the leading edge of the coin is brought into contact with the inside face of the finger 46, whereupon the cam 41 is rotated about its pivot 42 so as to carry its cam surface 43 into bearing contact with the opposed face of the coin 39. This initial or intermediate position of the cam 41 is best illustrated in Fig. 4 where, it will be observed, the engagement between the cam surface 43 and the opposed face of the coin 39 has caused the lock gate 29 to be rocked in a clockwise direction about its pivot pin 34, a distance sufficient to lift the lug 37 out of the path of the related sliding member 22. The sliding member 22 is now free to continue its sliding movement, pushing the coin 39 in advance thereof, during which movement the cam surface 43 rolls upon the face of the coin until such time as the finger 44 moves into the path of the sliding member 22 to effect positive ejection of the coin, as illustrated in Fig. 5. The ejected coin 39 falls into an enlarged chamber 48 provided for its reception by offsetting a portion of the main plate 15. The coin is then free to drop into the usual coin receptacle provided in machines of this character.

The slide members 22 are so constructed that they may be moved successively only. To this end, the lower sliding member 22 (Fig. 1) has a shoulder 51 normally abutted by a shoulder 52 on the adjacent sliding member 22. Similarly, said adjacent sliding member has a shoulder 51a, normally abutted by a shoulder 52a on the top sliding member 22. It should be quite apparent that when a 5¢ piece is deposited in the coin control mechanism it will come to rest upon a shelf 53 in the path of the lowermost sliding member 22. When the proper mechanism is actuated for vending a piece of merchandise having the value of five cents, only the lower one of the plurality of levers 28 is rocked, thus sliding the lowermost sliding member only. When a piece of merchandise having the value of ten cents is to be vended, two 5¢ pieces are deposited and come to rest in edgewise position upon the shelf 53, with one 5¢ piece in the path of each of the two lower sliding members 22. Consequently, manipulation of the vending mechanism for the purpose of vending a piece of merchandise having a value of ten cents will result in sliding movement of the two lower sliding members. Should there be but one 5¢ piece deposited in the coin control mechanism and the vending mechanism operable to vend a 10¢ piece of merchandise is actuated, said vending mechanism will be prevented from operating because the second sliding member will be prevented from being advanced with the lowermost sliding member owing to the presence in its path of the related lug 37.

In order to vend a piece of merchandise having a 20¢ value, four 5¢ pieces are placed in the coin control mechanism in the manner illustrated in Fig. 1 so as to thereby be effective to release the three sliding members 22, which

must necessarily be advanced in order to permit actuation of the vending mechanism provided for the vending of merchandise having a value of 20 cents.

Sliding motion of any one or all of the sliding members 22 must be completed to the ends of their stroke to prevent fraudulent manipulation of the device. In order to accomplish this, there is pivotally mounted on the main plate 15 a pawl 54 having an operating portion 55 and two leg portions 56. The pawl 54 is rotatably mounted, as by means of a rivet 57 and is maintained so that the portion 55 is normally in a vertical position by reason of the pull exerted thereon by a pair of coiled springs 58, which springs are attached to the legs 56 of the pawl 54 and to ears or pins 59 provided on a main plate 15. In operation as the lowermost sliding member 22 is moved to the right, the serrated edge 61 of a block 62, secured firmly to the sliding member 22, will engage the pawl 54 and move the same in a clockwise direction, thereby permitting the serrated edge to pass freely thereover. Obviously the sliding member 22 cannot be returned to its initial position prior to the portion 55 of the pawl 54 having cleared the serrated edge 61. When this occurs, the pawl 54 is free to be re-engaged by the serrated edge during the return movement of the lowermost sliding member 22.

It is believed that my invention, its mode of construction and assembly, and many of its advantages should be readily understood from the foregoing without further description, and it should also be manifest that while a preferred embodiment of the invention has been shown and described for illustrative purposes, the structural details are nevertheless capable of wide variation within the purview of my invention as defined in the appended claims.

I claim:

1. A coin control mechanism comprising a pair of spaced apart plates, means to direct a coin along a predetermined path between said plates, a plurality of sliding members arranged edge to edge between said plates, abutting shoulders on the opposed edges of said members to render said members selectively movable in succession, lock gates pivotally mounted on one face of one of said plates, each including a lug normally extending between said plates to prevent unlimited movement of the sliding members, cam members one pivotally mounted on each lock gate each having a portion extending between the plates, means to support coins in edge to edge relationship between the plates and in the paths of the sliding members, said coins engaging the cams to pivot the lock gates when the sliding members are initially moved and carry the lugs out of the paths of said sliding members to permit said members to complete a cycle of sliding operation, said cams having a rolling engagement with the coins after the lock gates have been lifted sufficiently to permit the sliding members to move the coins beneath the cams, and a second projecting portion extending from the terminal end of the cam surface, said projecting portion extending between said plates upon sufficient rotation of the cam for engagement by the sliding member, said second projecting portion causing further rotation of said cam.

2. A coin control mechanism comprising a pair of spaced apart plates, means to direct a coin along a predetermined path between said plates, a plurality of sliding members arranged edge to edge between said plates, abutting shoulders on the opposed edges of said members to render said members selectively movable in succession, pivotally mounted lock plates, each including a lug normally extending between said spaced plates to prevent unlimited movement of the sliding members, cam members one pivotally mounted on each lock plate each having a portion extending between the spaced plates, means to support coins in edge to edge relationship between the spaced plates and in the paths of the sliding members, said coins engaging the cams to pivot the lock plates when the sliding members are initially moved and carry

the lugs out of the paths of said sliding members to permit said members to complete a cycle of sliding operation, said cams having a rolling engagement with the coins after the lock plates have been lifted sufficiently to permit the sliding members to move the coins beneath the cams, and a second projecting portion extending from the terminal end of the cam surface, said projecting portion extending between said spaced plates upon sufficient rotation of the cam for engagement by the sliding member, said second projecting portion causing further rotation of said cam.

3. A coin control mechanism comprising a pair of spaced apart plates, means to direct a coin along a predetermined path between said plates, a sliding member between said plates, a lock gate pivotally mounted on one face of one of said plates, said lock gate including a lug normally extending between said plates to prevent unlimited movement of the sliding member, a cam member pivotally mounted on the lock gate having a portion extending between the plates, means to support a coin between the plates and in the path of said sliding member, said coin engaging the cam to pivot the lock gate when the sliding member is initially moved and carry the lug out of the path of said sliding member to permit said member to complete a cycle of sliding operation, said cam having a rolling engagement with the coin after the lock gate has been lifted sufficiently to permit the sliding member to move the coin beneath the cam, and a projecting portion extending from the terminal end of the cam surface, said projecting portion extending between said plates upon sufficient rotation of the cam for engagement by the sliding member, said projecting portion causing further rotation of the cam.

4. A lock gate for a coin control mechanism comprising an arm pivotally mounted at one end and having a projection at its other end adapted normally to limit movement of a sliding member in one direction, means to support a coin in the path of said sliding member, an eccentric carried by the arm engageable by the coin when the sliding member is initially moved in said one direction to cause the arm to move about its pivot in a direction that will render the projection ineffective, said eccentric having a rolling engagement with the coin after the arm has been lifted sufficiently to permit the sliding member to move the coin beneath the eccentric, and a projecting portion extending from the terminal end of the eccentric surface, said projecting portion extending into the path of the sliding member upon sufficient rotation of the eccentric for engagement by said sliding member, said projecting portion causing further rotation of the eccentric.

5. A coin control mechanism comprising a pair of spaced apart plates, a sliding member between said plates, a lock gate pivotally mounted on one face of one of said plates, said lock gate including a lug normally extending between the plates to prevent unlimited movement of the sliding member, a cam member pivotally mounted on the lock gate having a portion extending between the plates, means to support a coin between the plates in the path of the sliding member, said coin engaging the cam to pivot the lock gate when the sliding member is initially moved and carry the lug out of the path of said sliding member to permit said member to complete a cycle of sliding operation, said cam having a rolling engagement with the coin after the lock gate has been lifted sufficiently to permit the sliding member to move the coin beneath the cam and a second projecting portion on the cam, said projecting portion extending between the plates upon sufficient rotation of the cam for engagement by the sliding member, said projecting portion causing further rotation of the cam.

6. A coin control mechanism comprising a pair of spaced apart plates, a sliding member between said plates, a pivotally mounted lock gate, said lock gate including a lug normally extending between the plates to prevent unlimited movement of the sliding member, a cam mem-

ber pivotally mounted on the lock gate having a portion extending between the plates, means to support a coin between the plates in the path of the sliding member, said coin engaging the cam to pivot the lock gate when the sliding member is initially moved and carry the lug out of the path of said sliding member to permit said member to complete a cycle of sliding operation, said cam having a rolling engagement with the coin after the lock gate has been lifted sufficiently to permit the sliding member to move the coin beneath the cam and a second projecting portion on the cam, said projecting portion extending between the plates upon sufficient rotation of the cam for engagement by the sliding member, said projecting portion causing further rotation of the cam.

7. A coin control mechanism comprising a pair of spaced apart plates, a sliding member between said plates, a lock gate pivotally mounted on one face of one of said plates, said lock gate including a lug normally extending between the plates to prevent unlimited movement of the sliding member in one direction, a cam member pivotally mounted on the lock gate having a portion extending between the plates, means to support a coin between the plates in the path of the sliding member, said coin engaging the cam to pivot the lock gate when the sliding member is initially moved in said one direction and carry the lug out of the path of said sliding member to permit said member to complete a cycle of sliding operation, said cam having a rolling engagement with the coin after the lock gate has been lifted sufficiently to

permit the sliding member to move the coin beneath the cam, and coin engaging means on the cam engageable by the sliding member to eject the coin when the sliding member approaches the limit of movement in said one direction.

8. A lock gate for a coin control mechanism comprising a movable lock member adapted normally to limit movement of a sliding member in one direction, means to support a coin in the path of said sliding member, an eccentric mechanically connected to said lock member engageable by the coin when the sliding member is initially moved in said one direction to cause the lock member to move in a direction that will render said lock member ineffective, said eccentric having a rolling engagement with the coin after the lock member has been moved sufficiently to permit the sliding member to move the coin beneath the eccentric, and a projecting portion extending from the terminal end of the eccentric, said projecting portion extending into the path of the sliding member upon sufficient rotation of the eccentric for engagement by said sliding member, said projecting portion causing further rotation of said eccentric.
